(57) **CLAIM**

The ornamental design for a container having a helical grip, as shown and described.

DESCRIPTION

FIG. 1 is a perspective view of the container, embodying the new design;

FIG. 2 is a top view thereof;

FIG. 3 is a left view thereof;

FIG. 4 is a front view thereof;

FIG. 5 is a right view thereof;

FIG. 6 is a rear view thereof; and,

FIG. 7 is a bottom view thereof.

FIGS. 1-7 show features of a container having a helical grip in broken lines. These features are shown for environmental purposes and do not form any part of the claimed design. Further, the broken lines immediately adjacent the solid-line portions of the design form the boundary of the design, with the broken lines forming no part of the claimed design.
